UNITED STATES PATENT OFFICE.

ALBERTO LEITE RIBEIRO, OF CAMDEN, NEW JERSEY.

FOLDING CHAIR.

1,381,136.

Specification of Letters Patent. Patented June 14, 1921.

Application filed January 3, 1921. Serial No. 434,413.

To all whom it may concern:

Be it known that I, ALBERTO LEITE RIBEIRO, a citizen of the United States, and a resident of Camden, in the county of Camden and 5 State of New Jersey, have invented certain new and useful Improvements in Folding Chairs, of which the following is a specification, reference being had to the accompanying drawings.

10 A principal object of my invention is to provide a folding chair, stool, table or the like which, when unfolded and set up for use will be rigid, comfortable, of great strength and of pleasing and ornamental 15 appearance and which may be readily folded or collapsed from such position into a small and compact form for convenient transportation, storage or shipment. Further objects of my invention are to provide an article embodying the foregoing characteristics 20 which is simple in construction, design and operation and in which, when in unfolded or operative position, the several parts co-operate in such manner as to materially enhance 25 the rigidity and firmness of the structure.

My invention further comprehends the production of an article of the class described which may be manufactured and marketed at a relatively low cost, which is light in weight 30 and not easily damaged in use, and further comprehends all of the other various objects and novel features of construction and arrangement hereinafter more particularly specified and described.

35 It will be understood that my invention may be embodied in various articles of furniture such as chairs, stools, tables and the like, but for the purpose of enabling those skilled in the art to practise the invention I have 40 illustrated in the accompanying drawings and will not proceed to describe two slightly different forms thereof, that shown in Figures 1 to 4 inclusive being an armchair and that shown in Fig. 5 being a four-legged 45 stool without back or arm rest which also may be employed as a table.

In the said drawings, Fig. 1 is a perspective view of the chair in unfolded position and set up ready for use, the method of attaching or removing the back and arm rests being indicated in dotted lines. Fig. 2 is a 50 similar view with the back and arm rests removed and the method of attaching or removing the seat indicated in dotted lines.

Fig. 3 is a perspective view of the frame of 55 the chair in partly folded position, and Fig. 4 a view in side elevation of the frame of the chair in completely folded position. Fig. 5 is a perspective view of a slightly modified form of the invention.

60 Referring now more particularly to the form of the invention shown in Figs. 1 to 4 inclusive, the same comprises four vertically extending uprights 1, 1', 2, 2', which, when the device is in unfolded position, form the 65 corner posts thereof. These uprights are preferably formed of suitable light but rigid material, such as wood, and serve to pivotally or hingedly support the several struts and 70 braces hereinafter more particularly described. The uprights 2, 2' in this form of the invention are made somewhat longer than the front uprights 1, 1' so as to receive the back 4 and maintain the same in proper 75 position.

Respectively pivotally secured as by the 80 pivots 6 to the front uprights 1, 1' are members 7, 7' which, when extended, together form a transversely extending brace or cross member A. The members 7, 7' lie side by side and are pivoted together on a horizontal 85 pivot 8 preferably positioned equidistant from the pivots 6, the free ends of the members, that is, the ends opposite the pivots 6, being respectively beveled inwardly and downwardly so as to present diagonal surfaces 9, 9' for a purpose hereinafter set forth. It will be understood that the brace A is arranged so as to lie adjacent or slightly below 90 the seat when the chair is unfolded and that a substantially similar brace or cross member B is arranged at the back of the chair to extend between the uprights 2, 2' parallel 95 to the brace A and preferably in substantially the same horizontal plane. Similar braces or cross members C, D are arranged at the sides of the chair to extend respectively between the uprights 1, 2 and 1', 2' and at right angles, in the form of the invention shown, to the braces A and B. It will be 100 understood, of course, that the arrangement and construction of the members forming the braces B, C and D and the method of securing them to each other and to the several uprights, is preferably substantially the 105 same as has already been described with regard to the members forming the brace A, and it is therefore believed that further de-

tailed description thereof is unnecessary. However, the braces C and D are preferably secured to the uprights at points slightly higher than those at which the braces A and 5 B are secured thereto, so that the former when extended will lie in a horizontal plane slightly above the plane of the latter.

Pivots secured near the lower extremities of the uprights 1, 1' in any suitable 10 manner, as by the pivots 10, and extending diagonally upward therefrom but in opposite directions when the chair is in unfolded position, are a pair of struts 12, 12' which are arranged to cross each other at a 15 point 13 somewhere midway between their ends. The upper end of each of these struts is pivotally secured, as by the pivots 14, to one of the members 7, 7' forming the brace A, the strut 12' being secured to the member 20 7 at a point about midway between the pivot 8 and the pivot 6 and the strut 12 being similarly secured to the member 7', each strut and the member to which it is secured lying in the same vertical plane. 25 The points of attachment of the struts to the members are such that the beveled or diagonal surfaces 9, 9' respectively formed at the ends of each of the members will, when the chair is in unfolded position, contact with and bear firmly against the upper 30 surface of the adjacent strut whereby the several elements coöperate to maintain the uprights 1, 1' in vertical position and the members 7, 7' in horizontal position and 35 afford a rigid securely braced framework adapted to support a weight resting upon or acting downwardly against the cross member A. The upper ends of the struts 12, 12' are preferably beveled as at 16, 16' so as 40 to form a prolongation of the upper surface of the adjacent member of the brace, but these surfaces perform no function in enhancing the rigidity of the structure corresponding to that of the surfaces 9, 9'. 45 It will be understood that a pair of struts corresponding to the struts 12, 12' are provided at each side and the back of the chair to respectively coöperate with the braces C, D and B in a manner similar to that hitherto 50 described in connection with the brace A and struts 12, 12' at the front of the chair, so that when the device is unfolded, for example, as most clearly shown in Fig. 2, a very rigid framework is afforded adapted 55 to support a weight acting downwardly upon the braces and in which the corner uprights are maintained in vertical position and the several braces in horizontal position. This framework, however, may 60 be easily collapsed or folded by moving the uprights inwardly toward each other as best shown in Fig. 3, which operation, if continued, finally results in bringing the several parts to substantially the position 65 shown in Fig. 4, in which the framework

occupies a relatively small space and is adapted for convenient storage or transportation.

For the purpose of providing a seat when the device is used as a chair or stool or a 70 top when it is used as a table, a piece of heavy fabric, such as canvas or other suitable material, is employed and secured at its side edges in any suitable way to a pair of battens 20, 20' of sufficient length to extend 75 between the uprights 1, 2 and 1', 2' and slightly overlap them. Conveniently, the fabric seat 21 may be provided along its opposite edges with pockets 22, 22' for the 80 reception of the respective battens which can be slipped through the pockets and either permitted to rest loosely therein or else be permanently secured to the fabric by tacks or the like. The seat is assembled or removed from the framework in the 85 manner best shown in dotted lines in Fig. 2, that is, by engaging the ends of the battens projecting beyond the fabric over the outer faces of the uprights and lowering them into position to rest on the upper 90 surface of the braces C and D as shown in Fig. 1, in which position the fabric is tightly stretched and forms a convenient and comfortable seat which, however, may be readily removed when it is desired to fold the chair. 95 by lifting the battens upwardly to a point at which they may be readily disengaged from the uprights.

For the purpose of affording suitable back 100 rest and arm rests the back 4 may be employed, the same being formed of suitable fabric such as canvas and preferably comprising a sort of inverted pocket of suitable depth which is adapted to be slipped over the upper ends of the back uprights and 105 when in position thereon forms a comfortable support for the shoulders of a person seated in the chair; while extending forwardly from the back 4 are preferably provided a pair of flat strips of fabric 25, 25' 110 having rings 26, 26' or other means secured to their forward ends adapted to engage the upper ends of the front uprights of the frame, thereby affording convenient and comfortable arm rests for the occupant 115 of the chair. The manner of assembling the back and arm rests upon the frame is clearly indicated in Fig. 1 in which these parts are shown both in full lines in their assembled position and in dotted lines as 120 they are being brought thereto. It will, of course, be understood that ordinarily when the chair is folded the seat and back are rolled around the folded framework and either tied thereto or else slipped into a 125 bag or other receptacle therewith, for convenient transportation.

The form of the invention shown in Fig. 5 is substantially similar to that hitherto described save that the uprights are all made of 130

the same length and the back and arm supports omitted, the uprights terminating at a point just above the battens when the latter are in position and the device thus constituting a stool, camp chair or table.

While I have herein described certain forms of my invention with considerable particularity, I do not thereby desire or intend to limit myself specifically thereto, as minor changes and modifications may be made in the details of construction and arrangement as desired and the uses to which the invention may be put or the particular articles of furniture in which it may be embodied may be varied, so long as the same come within the scope and purview of the appended claims.

Having thus described my invention, I claim and desire to protect by Letters Patent of the United States:

1. A device of the class described comprising when in unfolded condition a plurality of vertically extending uprights located at the corners of the device, cross members extending horizontally in opposite directions between each pair of adjacent uprights, each of said members being pivoted adjacent its outer end to one of said uprights and having its inner end beveled diagonally downward, a pivot connecting said members, and a pair of struts, each member of the pair being pivoted near its lower end to one of said uprights and near its upper end to one of said cross members and each strut being in co-operative engagement with the beveled end of another of said members to support said member in horizontal position.

2. A device of the class described comprising when in unfolded condition a plurality of vertically extending uprights located at the corners of the device, a pair of cross members extending horizontally in opposite directions between each pair of adjacent uprights, each of said members being pivoted near its outer end to one of said uprights, a pivot connecting said members, the free end of each member extending beyond said pivot, and a pair of struts, each member of said pair being pivoted adjacent its lower end to one of said uprights and adjacent its upper end to one of said members, each strut engaging and supporting the free end of the other member to maintain said member in horizontal position, said cross members and struts in folding permitting the device to collapse at all sides of the same.

3. A device of the class described comprising when in unfolded condition a plurality of vertically extending uprights located at the corners of the device, a pair of cross members positioned side by side and extending horizontally between each pair of adjacent uprights and in opposite direc-

tions, each of said members being pivoted adjacent its outer end to one of said uprights and having its free inner end overlapping the other member, a pivot connecting said members at a point equidistant from their points of attachment to said uprights, and a strut pivoted to each of said uprights adjacent the lower end thereof and extending upwardly therefrom and pivoted to one of said members, said struts crossing each other below said members and each engaging the free end of the member opposite to that to which the strut is pivoted to support said member in horizontal position, said cross members and struts in folding permitting the device to collapse at all sides of the same.

4. A device of the class described comprising when in unfolded condition a plurality of vertically extending uprights located at the corners of the device, a plurality of horizontally extending members each pivoted at one end to one of said uprights and having its free end beveled diagonally downward, a pair of said members being respectively arranged on each side of said device and on the front and back thereof, extending in opposite directions, overlapping each other and being pivotally secured together to form a brace, a plurality of upwardly angularly extending struts each pivoted adjacent its lower end to one of said uprights and pivoted adjacent its upper end to the member extending from the opposite upright on that side of the device, the upper face of each strut engaging the beveled end of the other of said pair of members and being co-operative therewith to maintain said member in horizontal position, said cross members and struts in folding permitting the device to collapse at all sides of the same.

5. The combination with a device of the class described comprising a plurality of vertically extending uprights and means for maintaining said uprights in vertical position, of a removable seat comprising a fabric portion and a pair of battens disposed in parallel relation adjacent the side edges of said fabric and adapted to engage the faces of said uprights at the outside thereof to maintain said fabric in extended position therebetween.

6. The combination with a device of the class described comprising a plurality of vertically extending uprights and means for maintaining said uprights in vertical position, of a removable seat comprising a fabric portion having pockets formed at two of its opposite edges, a batten in each of said pockets extending beyond the edges of said fabric and in opposite directions therefrom, said battens engaging the exterior faces of said uprights to maintain said fabric in tensioned condition therebetween.

7. The combination with a device of the

class described comprising a plurality of vertically extending uprights, a removable seat and means for maintaining said seat in horizontal position between said uprights, of 5 a back and arm rest comprising an inverted pocket of flexible material adapted to engage the upper extremities of two of said uprights, a strip of flexible material extending from said pocket, and means for securing 10 the free end of said strip to another of said uprights.

8. The combination with a device of the class described comprising four vertically extending uprights, means for maintaining 15 said uprights in vertical position, a remov-

able seat and means for holding said seat in operative position between said uprights, of a back and arm rest comprising an inverted pocket formed of fabric and adapted to engage over the extremities of the two uprights 20 forming the back legs of the device, and a pair of spaced strips of fabric secured to and extending forwardly from said pocket, and means operative to secure the free ends of said strips to the uprights forming the 25 front legs of the device.

In witness whereof, I have hereunto set my hand this 31st day of December, 1920.

ALBERTO LEITE RIBEIRO.
